UNITED STATES PATENT OFFICE.

HARRY L. BECK, OF PITTSBURGH, JOHN WEIBLE, OF CORAOPOLIS, AND JERRY J. HOULAHEN, OF MILLVALE, PENNSYLVANIA.

FUSE.

1,274,368.

Specification of Letters Patent.

Patented Aug. 6, 1918.

Application filed October 4, 1915. Serial No. 53,932.

To all whom it may concern:

Be it known that we, HARRY L. BECK, JOHN WEIBLE, and JERRY J. HOULAHEN, citizens of the United States, and residents 5 of Pittsburgh, Coraopolis, and Millvale, respectively, in the county of Allegheny and State of Pennsylvania, have invented a new and useful Improvement in Fuses; and we do hereby declare the following to be a 10 full, clear, and exact description thereof.

Our invention relates to a fuse for electric circuits.

The invention relates more particularly to that type of fuse in which the shell or casing is provided with a movable shutter by the removal of which the fuse is exposed and can be readily removed and a new one inserted; the object of our invention, however, being to provide a fuse of this type in which 20 the parts are so arranged that a careless person cannot close up the shell or casing without all the parts being assembled in their proper position—such as omitting to put the shutter in position thereby leaving the fuse 25 exposed. A further object of our invention is to simplify the construction and reduce the number of separate parts, whereby the 30 operation of removing and inserting a new fuse is greatly simplified and the time required is reduced to a minimum.

Referring to the accompanying drawing, Figure 1 is a longitudinal view of our improved fuse; Fig. 2 is a longitudinal view with the shutter removed; Fig. 3 is a view 35 of the shutter removed; Fig. 4 is a side view of the detached cap; Fig. 5 is a plan view thereof; Fig. 6 is a sectional view of same; Fig. 7 is an end view of the cap attached to the shutter; Fig. 8 is a cross-section on the line 8—8, Fig. 1; Fig. 9 is a cross-section on the line 9—9, Fig. 1; and Fig. 10 is a view of the fuse-wire removed.

The numeral 2 designates a suitable shell or casing formed of fiber or other suitable material, said casing having the opening 3, which is normally closed by the shutter 4. This shutter is provided with the tongue 5 and the shoulder 6 whereby said shutter has a longitudinally sliding connection with the shell 2.

Connected to one end of the shutter 4 is the cap 7, said cap having the slotted opening 8 and the vents 9.

Secured within the shell 2 by the screws 10 55 are the terminals 11. These terminals rest

against a shoulder 12 on the inside of the shell and when the shutter 4 is inserted, the tongues 5 of said shutters engage the terminals, and in this way the terminals are held securely between the shoulders 12 and 60 the tongues 5, as clearly indicated in Fig. 8.

The fuse-wire 13 is connected by the screws 14 to the terminals 11, 11^a, washers 15 being employed to practically cover the ends of the fuse-wire and hold the same securely 65 in position. The fuse-wire is provided with an opening 16, which engages the similarly-shaped stud 17 on one of the terminals 11^a. The shape of this opening 16 and of the stud 17 may vary for different sized fuse-wires so that a person in applying a fuse-wire can only apply the proper size as unless the shape of the opening in the fuse-wire corresponds to the shape of the stud on the terminals, the fuse-wire cannot be inserted into position. This insures the proper 70 size of fuse-wire always being employed and prevents a careless person from putting in a fuse-wire which will not give the proper 75 results.

A removable cap 18 is connected to the shell 2 by the bayonet-joint connection 19. A swivel-plate 20 is secured to the cap 18, said plate having the tongues 21 secured thereto which overlap the flange 22 of the 80 cap. In this manner, the swivel-plate is held within the cap, but said cap is free to rotate independently of said swivel-plate. The swivel-plate has the slotted opening 23 through which the terminal 11 passes. By 85 the above construction, the cap can be turned to disconnect said ferrule from the shell 2, while the swivel-plate 20 is held from turning by the terminal which passes through the slotted opening 23 therein. 95

When the fuse-wire has burned out and it is desired to replace it with a new one, the cap 18 is first removed by releasing the bayonet-joint whereupon the shutter 4 may be slid out, said shutter carrying with it the 100 cap 7. When the shutter has been removed, the screws 14 are unscrewed and the burned fuse-wire removed. A new fuse-wire is substituted and in order to insert said fuse-wire, the opening 16 therein must be of 105 proper shape and size to fit over the stud 17. This insures against the insertion of the wrong size of fuse-wire, and different shaped openings and studs will be provided for different sized fuse-wires. A careless per- 110

son is in this way prevented from slipping in a fuse-wire which is not capable of doing the work. When the fuse-wire has been adjusted in place, the operator then slips the shutter 4 back into position, and as the cap 7 is permanently attached to the shutter, there is no liability of inserting the cap without the shutter so that all liability of leaving the fuse-wire exposed is obviated. 10 When the shutter and the cap 7 have been adjusted in position, the cap 18 is then slipped on the other end and the bayonet-joint secures the cap to the shell and to the shutter.

15 By having the washer or swivel-plate 20 connected to the cap 18, the cap cannot be adjusted in position without the swivel-plate which closes up that end of the fuse-plug and prevents a careless person from failing 20 to insert the suitable plate or washer, which is liable to happen where the plate 20 is separate from the cap.

By our invention, the parts are so adjusted and arranged that there is never any 25 liability of any part being omitted which is necessary to close up the fuse-plug completely, and there is no opportunity for the emitting of any sparks and the loss of fire which is liable to follow.

30 What we claim is:

1. In a fuse, the combination of a suitable shell or casing having a longitudinally extending opening, terminals in said shell extending beyond the ends thereof, a fuse wire 35 connected to said terminals, a shutter slideable in said opening, a cap permanently con-

nected to said shutter adapted to close one end of said shell, and a cap closing the opposite end of said shell having a freely detachably locking connection with said shutter whereby said removable cap will lock both caps in position.

2. In a fuse, the combination of a suitable shell or casing having a longitudinally extending opening, terminals secured therein 45 extending beyond the ends thereof, a fuse wire connected to said terminals, a cap on one end of said shell, a swivel plate on said cap through which one of said terminals passes, a slideable shutter engaging said opening, a cap connected to said shutter, and means connecting said first named cap and said shutter.

3. In a fuse, the combination of a suitable shell or casing having a shoulder therein, a 55 terminal engaging said shoulder, said shell having a longitudinally extending opening therein, a slideable shutter engaging said opening, said shutter having tongue portions engaging said terminal whereby said terminal is held between said shoulder and said tongue portion.

In testimony whereof we, the said HARRY L. BECK, JOHN WEIBLE, and JERRY J. HOULAHEN, have hereunto set our hands.

HARRY L. BECK.

JOHN WEIBLE.

JERRY J. HOULAHEN.
